US0D1042418S

(12) **United States Design Patent** (10) **Patent No.:** **US D1,042,418 S**
(45) **Date of Patent:** **** Sep. 17, 2024**

(54) **MICROPHONE**

(71) Applicant: **Audio-Technica Corporation**, Tokyo (JP)

(72) Inventors: **Junya Uchida**, Tokyo (JP); **Wataru Suzuki**, Tokyo (JP)

(73) Assignee: **AUDIO-TECHNICA CORPORATION**, Tokyo (JP)

(**) Term: **15 Years**

(21) Appl. No.: **29/867,921**

(22) Filed: **Nov. 14, 2022**

(30) **Foreign Application Priority Data**

May 31, 2022 (JP) ..... 2022-011684 D

(51) **LOC (14) Cl.** **14-01**

(52) **U.S. Cl.**

USPC **D14/225**; D14/226

(58) **Field of Classification Search**

USPC D14/225, 226, 227-229; 181/290, 284, 181/158; 381/368

(57) **CLAIM**

The ornamental design for a microphone, as shown and described.

DESCRIPTION

FIG. 1 is a top, rear, right side perspective view of a microphone, showing the new design;

FIG. 2 is a bottom, front, left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

Evenly broken lines depict portions of the microphone which form no part of the claimed design.

1 Claim, 4 Drawing Sheets
